(57) **CLAIM**

The ornamental design for a receptacle for optical fiber connector, as shown and described.

DESCRIPTION

FIG. 1 is a left, front perspective view of a first embodiment of a receptacle for optical fiber connector showing our new design;

FIG. 2 is a left, rear perspective view thereof;

FIG. 3 is another left, front perspective view thereof;

FIG. 4 is a front view thereof;

FIG. 5 is a rear view thereof;

FIG. 6 is a left side view thereof;

FIG. 7 is a right side view thereof;

FIG. 8 is a top view thereof;

FIG. 9 is a bottom view thereof;

FIG. 10 is a left, front perspective view of a second embodiment of a receptacle for an optical fiber connector showing our new design;

FIG. 11 is another left, front perspective view thereof;

FIG. 12 is left, rear perspective view thereof;

FIG. 13 is a front view thereof;

FIG. 14 is a rear view thereof;

FIG. 15 is a left side view thereof;

FIG. 16 is a right side view thereof;

FIG. 17 is a top view thereof;

FIG. 18 is a bottom view thereof;

FIG. 19 is an enlarged view of portion A indicated in FIG. 3;

FIG. 20 is an enlarged view of portion B indicated in FIG. 1;

FIG. 21 is an enlarged view of portion C indicated in FIG. 2;

FIG. 22 is an enlarged view of portion D indicated in FIG. 10;

FIG. 23 is an enlarged view of portion E indicated in FIG. 11; and,

FIG. 24 is an enlarged view of portion F indicated in FIG. 12.

The broken lines in the figures are for the purpose of showing unclaimed environmental structure only and form no part of the claimed design.
